[57] CLAIM

The ornamental design for a plastic container with integral handle, as shown and described.

DESCRIPTION

FIG. 1 is top, rear and left side perspective view of a plastic container with integral handle showing our new design; FIG. 2 is a left side elevation of the plastic container with integral handle, the right side elevation is a mirror image thereto;

FIG. 3 is a front elevation view thereof;

FIG. 4 is a rear elevation view thereof;

FIG. 5 is a top plan view thereof;

FIG. 6 is a bottom plan view thereof;

FIG. 7 is a top, rear and left side perspective view of a second embodiment of the plastic container with integral handle;

FIG. 8 is a left side elevation of the plastic container with integral hand, the right side elevation is a mirror image thereto;

FIG. 9 is a front elevation view thereof;

FIG. 10 is a rear elevation view thereof;

FIG. 11 is a top plan view thereof; and

FIG. 12 is a bottom plan view thereof.

The broken lines showing the dispensing opening of the container are for illustrative purposes only and form no part of the claimed design.
